UNITED STATES PATENT OFFICE

2,466,834

BOW FOR VIOLINS AND OTHER STRINGED INSTRUMENTS

Percy Gordon Attwood, Oldbury, England, assignor to Accles & Pollock Limited, Oldbury, England

Application May 20, 1947, Serial No. 749,171
In Great Britain May 28, 1946

2 Claims. (Cl. 84—282)

1

This invention relates to bows for violins and other stringed instruments, of the kind in which the staff of the bow is made from a steel or other metal tube. It has been found that such a bow possesses an undesirable resonance due to vibrations within the staff when the bow is in use, and the object of the invention is to provide an improved bow in which this undesirable quality is minimised or eliminated.

The invention comprises a staff made from metal tube and having a packing or lining of sound-absorbent material.

The accompanying drawing is a part sectional side view of a violin bow staff embodying the invention.

In carrying the invention into effect as shown, I construct the staff *a* from steel or other suitable metal tube, as heretofore, and I lightly pack the interior of the tube with kapok, cotton, wool, or any other analogous fibrous material *b* (which may include glass wool or the like).

Alternatively instead of lightly packing the staff *a* as above described, I may line it with any appropriate sound absorbent material, such as paper, or fabric, or a deposit of powdered material.

2

I find that by the simple expedients above described, the undesired resonance can be eliminated or reduced to any desired extent.

Having thus described my invention what I claim as new and desire to secure by Letters Patent is:

1. A staff for the bow of a violin or other stringed instrument, consisting of a metal tube, and sound-absorbent material contained in the tube throughout at least the greater part of the length of the tube.

2. A staff as claimed in claim 1, in which the sound-absorbent material is of fibrous structure.

15 PERCY GORDON ATTWOOD.
